UNITED STATES PATENT OFFICE.

WILLIAM H. HAIRE, OF MORRISTOWN, TENNESSEE, ASSIGNOR OF ONE-HALF
TO GEORGE K. TURNER, OF SAME PLACE.

RATCHET-WRENCH.

SPECIFICATION forming part of Letters Patent No. 449,476, dated March 31, 1891.

Application filed December 18, 1890. Serial No. 375,069. (No model.)

To all whom it may concern:

Be it known that I, WILLIAM H. HAIRE, of Morristown, in the county of Hamblen and State of Tennessee, have invented a new and useful Improvement in Ratchet-Wrenches, of which the following is a full, clear, and exact description.

My invention relates to ratchet-wrenches, and has for its object to simplify the construction of such articles and provide an economic and durable tool capable of use in any manner in which an ordinary wrench may be employed and possessing the advantage of being conveniently manipulated right or left in exceedingly limited spaces.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a partial plan and horizontal sectional view of the tool. Fig. 2 is a vertical section taken on the line 2 2 of Fig. 1. Fig. 3 is an end view of the head of the wrench; and Fig. 4 is a bottom plan view of the adjustable jaw.

The head of the wrench A comprises practically a fixed jaw 10 and an adjustable jaw 11. The fixed jaw 10 consists of a horizontal block member *a*, which may be in the shape of a disk or of an oval or other contour, and a clamping member *a'*, the inner face whereof is straight, though it may be serrated or roughened if in practice it be found desirable. In the horizontal block member *a*, at its outer end, an undercut recess 12 is produced, which extends almost to the opposite end and through the under face, forming thereby a slideway, as is best illustrated in Figs. 2 and 3, the recess being more or less T-shaped in cross-section. The adjustable jaw consists of a horizontal block member *b*, essentially T-shaped in cross-section, as shown in Fig. 3, and of suitable size to slide in the recess 12 of the fixed jaw, and from the block member *b* of the jaw 11 a clamping member *b'* is downwardly projected, having a smooth or a serrated inner face. The adjustment of the jaw

11 is effected through the medium of a screw 13, which screw is held and turns freely in an aperture 14, produced in the end of the block-section of the fixed jaw facing the handle, and the threaded portion of the screw is made to enter a threaded horizontal aperture extending through the block-section of the movable jaw from end to end thereof. A post or stud 15 is attached to or formed integral with the upper surface of the block-section of the stationary jaw, and around the stud or post the outer end of a handle *B*, which may be of any approved construction, is held to freely turn. To that end the handle is provided with an opening, through which the stud or post 15 passes. Upon the upper end of the post a cap-block 16 is rigidly secured, preferably through the medium of a set-screw 17, as is best shown in Fig. 2, the said cap-block being adapted to almost engage at its under face with the upper face of the handle, and around the periphery of the lower portion of the cap-block a series of teeth 18 is produced, as is best shown in Figs. 1 and 3. The outer end of the handle adjacent to the head is flattened to such an extent as to provide a shoulder 19, and in this shoulder a bore is produced, in which a spring-pressed bolt 20 is held to slide, and the head of the bolt is adapted to normally engage with either one side face or the other of an essentially triangular dog 21, pivoted upon the upper face of the handle between the shoulder and the toothed face of the cap-block. The edge of the dog facing the cap-block is preferably concaved at its center, as illustrated at *d* in Fig. 1, and is also provided with a concaved surface *d'* at each end, whereby spurs 22 are formed, adapted to enter the spaces between the teeth and engage therewith.

In operation the jaws are fitted to clamp any size of nut or other object by manipulating the screw 13, which carries the jaw 11 toward or from the jaw 10. The wrench may now be manipulated to turn the nut or other object clamped thereby either to the right or to the left by causing one or the other of the spurs of 22 the dog to engage with the toothed surface of the cap-block. When the handle is carried in one direction, the dog will force the cap-block to revolve, which in turn will

rotate the jaws; but when the handle is moved in the opposite direction the dog slips over the teeth and has no action thereon. The dog is held in either one of its two positions by the bolt 20, and these positions may be readily changed, as the head of the bolt is conical, which permits the apex or point of the dog to readily pass it when being shifted.

Having thus described my invention, I claim to as new and desire to secure by Letters Patent—

1. In a ratchet-wrench, the combination, with a stationary jaw, a movable opposed jaw, an adjusting-screw held to turn in the fixed 15 jaw and fitted to a threaded opening in the movable jaw, and a stud projected upward from the fixed jaw, of a handle held to revolve around the stud, a cap-block secured to the upper end of the stud and provided with a toothed periphery, and a spring-pressed dog 20 pivoted upon the handle provided with two spurs adapted for engagement with the toothed periphery of the cap-block, as and for the purpose specified.

2. In a ratchet-wrench, the combination, with a head comprising two jaws, a fixed jaw consisting of a horizontal block-section having a stud integral with its upper face, an essentially T-shaped recess formed in its under 25 face and at one end, and a gripping or clamping section extending vertically down from the block-section, and a movable jaw consisting of a horizontal block-section adapted to slide in

the recess of the corresponding section of the fixed jaw, and a downwardly-extending clamp- 35 ing-section, and a screw held to turn in the horizontal section of the fixed jaw, the threaded surface whereof is fitted to the aperture in the movable jaw, of a handle held to loosely turn upon the stud, a cap-block secured to the outer 40 end of the stud, provided with a toothed peripheral surface, and a spring-pressed essentially triangular dog pivoted upon the handle provided with two spurs adapted for engagement with the toothed surface of the cap- 45 block, as and for the purpose specified.

3. In a ratchet-wrench, the combination, with two jaws, one sliding in the other, an adjusting-screw held to loosely turn in one jaw and fitted to a threaded opening in the opposite jaw, a post projected upward from the fixed jaw, and a cap-block secured upon the upper end of the post and provided with a toothed peripheral surface, of a handle held to freely turn around the post between the 55 jaws and the cap-block, an essentially triangular dog pivoted upon the handle provided with two spurs adapted for engagement with the toothed surface of the cap-block, and a spring-pressed bolt located in the handle and 60 having a bearing against the dog, as and for the purpose specified.
